US00D778747S

(12) **United States Design Patent** (10) Patent No.: **US D778,747 S**
Lebrat (45) Date of Patent: **** Feb. 14, 2017**

(54) **SPORT MEASURING INSTRUMENT**

(71) Applicant: **SMART2MOVE AG**, Basel (CH)

(72) Inventor: **Gregory Lebrat**, Basel (CH)

(73) Assignee: **Smart2Move AG**, Basel (CH)

(**) Term: **15 Years**

(21) Appl. No.: **35/500,494**

(22) Filed: **Nov. 23, 2015**

(80) **Hague Agreement Data**

Int. Filing Date: **Nov. 23, 2015**

Int. Reg. No.: **DM/088860**

Int. Reg. Date: **Nov. 23, 2015**

Int. Reg. Pub. Date: **Jan. 15, 2016**

(51) **LOC (10) Cl. 10-04**

(52) **U.S. Cl.**

USPC **D10/92**

(58) **Field of Classification Search**

USPC D10/83, 87-88, 92; D21/671

See application file for complete search history.
